UNITED STATES PATENT OFFICE

2,583,553

SANITARY PROTECTOR FOR BEDRIDDEN PATIENTS

Marthe E. C. Faure, Tulsa, Okla., assignor to Faureed Company, Tulsa, Okla.

Application April 7, 1949, Serial No. 86,016

1 Claim. (Cl. 128—287)

1

The present invention relates to a moisture-proof protective covering for disposable and similar pads and washable or disposable diapers which are now being commonly used for the comfort of bedfast and bedridden patients in homes, hospitals and elsewhere.

Instead of using bedpans it is the accepted practice in handling aged and invalid persons to employ disposable pads, wads or raw cotton and in some instances washable diapers and many and varied make-shift devices are used to apply and retain such articles in place against the user's body. As a general rule, however, it is almost necessary, to protect bed clothing and mattress, to use rubber sheets. It is common knowledge that rubber sheets, especially in warm climates, are troublesome and cause sweating and bed sores.

More explicitly, my invention has to do with a simple and economical moisture-proof covering which is of minimum proportions to conform to the anatomy and to form-fit the wearer, the same being sufficient to fasten padding and the like against the needed portions of the body and, in so doing, to comfort and keep the patient clean, to eliminate rubber sheeting, to minimize the job of constantly changing bed clothing and to otherwise make more practical the practice of using adult size diapers for bedfast persons, incontinent patients and the like.

In carrying out the principles of the invention, I utilize a sheet of waterproof material of so-called commercial plastic-film the same being generally triangular in marginal outline and providing a body and hips encircling portion and a slender elongate appendage which is adopted to be drawn between the user's legs and in up over the abdomen and tied in place in order to satisfactorily hold the padding in proper relationship to the wearer's buttocks and anus without undue stress and binding.

Another object is to provide the aforementioned triangular protector sheet whose marginal edges are free of usual over-the-edge bindings but are provided, inwardly of the edges, with reinforcing tapes to impart the desired fixed shape to the overall protector and to render same comparatively strong and durable.

Other objects and advantages will become more readily apparent from the following description and the accompanying illustrative drawings.

In the drawings:

Figure 1 is a fragmentary perspective view of the patient showing the improved protector

2

shield or covering and illustrating the manner in which the same is applied and worn.

Figure 2 is a top plan view of the protector per se.

Figures 3 and 4 are enlarged fragmentary detail sections on the lines 3—3 and 4—4, respectively, of Figure 2, looking in the direction of the arrows.

Referring now to the drawings by distinguishing reference numerals and accompanying lead lines, the protector is a one-piece item and is susceptible of being made from any appropriate waterproof material. For lightness of weight and conformability and ease of washing and reusing, I have found a thin, flexible, water-proof sheet or so-called plastic-film and use of same has proved to be meritorious and successful. It is obvious, however, that it is not the texture or kind of material that I am interested in but rather in the use of what I generally refer to as an approximately triangular sheet of thin moisture-proof, flexible material of the more acute shape shown in Figure 2. It is to be assumed that the main body portion of this sheet constitutes a body encircling member and the latter is identified by the numeral 6 and includes wrap-around or end flaps 7 and 8 which, in use are tied together, without necessarily touching, over the abdomen of the wearer as brought out in Figure 1. The slight incurved portions along the marginal edges permit the body encircling member to more or less conform to the anatomy and particularly the buttocks and hips and the appendage portion of the sheet may be referred to as an apron, the same being long and slender and adapted to fit between the legs and then drawn up over the abdomen where it is attached to the coacting ends of the flaps 7 and 8. This apron causes the overall sheet to draw in and conform to the anatomy, that is the buttocks, and to fit the pelvic area, to thus hold the padding 9 in place. This apron portion is denoted by the numeral 10. Incidentally, and as previously touched upon, it is not the padding or filler 9 with which I am concerned but only the protector which holds the padding in proper position in relation to the coacting parts of the wearer. The straight across marginal edge 11 of the body encircling portion is provided, on one surface of the sheet, with a tape 12 which we will call the body encircling tape, and this is stitched in place as at 13. Incidentally, all of the tapes are of the type shown in Figure 4 wherein the tape has inturned edge portions 14 and 15 stitched in place in the manner shown.

In Figure 4, one surface of the sheet is denoted at 16 and the other surface is denoted at 17 and it is this surface to which said tapes are sewn. The free or unattached ends of the body encircling tape are denoted at 18 and 19 and are adapted to be tied together into a bow-knot or the like as shown in Figure 1. The coacting converging tapes, which we see spaced inwardly from the edges 20 and 21, are denoted by the numerals 22 and 23 and these are stitched down as at 24. They come to a point or converge at the small tip end of the apron 10 and are provided with a double-ended auxiliary tying tape 25 having free ends 26 and 27. These free ends may be tied to the already tied ends 18 and 19 so as to provide for minimum of coverage of the user's body but to at the same time reliably hold the needed padding in ready-to-use position at all times.

In connection with the tapes it should be particularly noted that they are superimposed against the so-called inner surface of the sheet and spaced slightly inwardly from the coacting marginal edges. This serves to reinforce all marginal edges and to provide the proper ties and at the same time this marginal tape may contact the body of the wearer. The advantages of this tape to body contact are: It prevents or reduces chafing by permitting ventilation under the water-proof covering and so helps dissipate the heat that is trapped under said covering. The tape has the ability to absorb perspiration which is a natural result to covering the body with a non-porous material. The tape minimizes the contact of the water-proof material with the skin of the wearer, otherwise, such contact tends to be irritating, especially around the marginal edges when the garment is drawn snugly to the body. Although the preferred and most advantageous way for the cover is preferably worn with the taped side 17 contacting the patient's body, it can and may be effectively worn (as shown) with the taped side not touching the body.

My protector has been designed especially for adults because of the desirability, if not the necessity, of removing as much as possible the extra preparation of the bed and for the easy manipulation and application in the handling and care of such cases; it gives protection and comfort to the patient.

The simplicity of design was considered in order to make the patient comfortable by eliminating so much padding, heavy binding, cover as little of the body and to provide more freedom of action and circulation, thus avoiding the possibility of bed sores due to constant usage.

The material selected was chosen as the best for lightness in weight, wearing and sanitary qualities; the padding for easy disposal, laundering, absorbency and economy.

It is to be understood that the protector covering herein shown and described is not necessarily confined for use by hospitalized and bed-ridden patients, for it may be satisfactorily and aptly used by any incontinent patient or person, convalescent, or one partially incapacitated or, for that matter, by normal persons. It is strong, and light in weight and may be appropriately

worn under one's clothing without revealing bulkiness or impairing freedom of movement of the wearer's parts. It virtually "molds" itself to comfortably and snugly fit the parts of the anatomy with which it coacts. In it, manufacturers and users will find their expected needs fully met, contained and aptly available.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

A washable re-usable protector-type readily applicable and removable cover and retainer for absorbent pads commonly used to take the place of a bedpan comprising a triangulated single ply sheet of thin pliant water-proof material embodying a back portion having a straight across edge and a crotch portion, said back portion having free terminal tying and retaining flaps adapted to overlie the abdomen of the wearer, said crotch portion being an appreciably slender tapering apron which is conformingly adapted to be drawn upwardly between the wearer's legs and then up over the abdomen, a fabric tape superimposed against one surface of said back portion and attached thereto just inwardly of and parallel to the straight across edge of the latter, the areal extent of attachment of said tape ranging from the tip of one flap to the tip of the remaining flap and the ends of said tape being free and projecting well beyond the terminal ends of said flaps, a single pair of additional fabric tapes superimposed against said one surface and ranging from the attached end portions of said first named tape and extending uninterruptedly along the two remaining marginal edges of the back and apron portions of said material and being fastened to the latter slightly inwardly of the corresponding marginal edges of said back and apron portions and being joined together at the apex end of said apron, and a pair of tying elements fastened to the junctural portions of said pair of tapes, said apron being of a length which allows said apex end to be drawn up over the abdomen of the wearer and interposed between the terminals of said flaps, whereby said tying elements may be tied to the free ends of said first named tape after said free ends are tied into a bow-knot.
